ALFRED MORRIS THOMSON, OF NEWARK, NEW JERSEY, ASSIGNOR TO DARDELET THREADLOCK CORPORATION, OF NEW YORK, N. Y., A CORPORATION OF DELAWARE

APPARATUS FOR TESTING SUCKER RODS

Application filed October 17, 1929. Serial No. 400,262.

An important object of the present invention is to provide an efficient and reliable apparatus for testing the strength of sectional sucker rods such as are employed in oil wells. Such rods are often extremely long and formed of a great many rod sections separably coupled together end to end. When one of these long rods is reciprocated in a well by the pumping machinery it is subjected to severe longitudinal and lateral strains which cause it to bend or buckle at many points along its length and cause it to vibrate, and to pound and scrape against the well casing. A severe strain is thereby imposed upon the rod couplings and frequently causes them to unscrew or break. When this occurs it is extremely difficult to recover the lower length of the broken rod.

The present invention provides for a thorough preliminary testing of the rod sections and their couplings by subjecting said parts to strains as nearly as possible like those of actual service. The invention further provides for the performance of the test in a convenient manner, provides for varying the severity of the test, and enables the results of the test to be readily observed.

In the drawing, Fig. 1 is a side view of the apparatus upon a greatly reduced scale;

Fig. 2, a longitudinal sectional view of the apparatus upon a larger scale;

Fig. 3, a plan view of the apparatus;

Fig. 4, a longitudinal section upon a still larger scale taken approximately on the line 4—4 of Fig. 2;

Fig. 5, a transverse section taken on the line 5—5 of Fig. 4;

Fig. 6, a transverse section taken on the line 6—6 of Fig. 2;

Fig. 7, a side view, partly in section, of the coupling between a pair of rod sections; and

Fig. 8, a side view, partly in section, of one of the joints between the rod and the testing apparatus.

The testing apparatus includes a base or supporting structure comprising a pair of I-beams 1 rigidly supported horizontally in spaced parallel relation, with their webs vertical. At one end of said pair of beams is mounted a power driven mechanism 2 adapt-

ed to be operatively connected to a sectional, coupled sucker rod for reciprocating it longitudinally of the beams. Mounted at the opposite end of the pair of beams is a hydraulic press device 3 also adapted to be connected to the sucker rod for resisting its movement. Between the press device and the power mechanism, a tubular section or cage 4 is mounted and disposed to surround the coupling means of the sucker rod and substantially duplicate the conditions under which the rod operates when confined in a well casing.

The power driven mechanism 2 for reciprocating the sucker rod includes a crank 5 disposed between the beams and formed by a pair of spaced disks 6 rigidly connected by a crank pin 7 and fixed to two shaft sections 8. The latter are disposed transversely of the beams and are rotatably mounted in bearings 9 supported by the webs of the beams. Mounted upon the upper flanges of the beams is an electric motor 10 for driving the crank. Upon the motor shaft is fixed a drive pinion 11 which meshes with a gear 12 of relatively large diameter fixed to one end of a shaft 13. The latter is rotatably mounted in bearings 14 mounted upon the beams and has a small pinion 15 fixed to its opposite end. Pinion 15 meshes with a relatively large gear 16 fixed upon one of the crank shaft sections 8. Thereby a reduction drive gearing is formed between the motor and the crank.

The hydraulic press device 3, at the opposite end of the pair of beams, comprises a pair of cylinders 17 and 18 disposed in axial alignment between and along the beams and rigidly secured thereto as at 19. Said cylinders are spaced apart along the beams and their inner, opposed, ends are open. Between the cylinders is a combined crosshead and piston member forming a central crosshead 20, a ram or piston 21 extending from one end of said crosshead and a ram or piston 22 extending from the opposite end of the crosshead, all integrally formed or secured rigidly together. Ram 21 is fitted for reciprocation in cylinder 17 and ram 22 is fitted for reciprocation in cylinder 18. Between the beams 1, inwardly of the cylinder

18, is a second crosshead 23 rigidly and operatively connected to the crosshead 20 by rods 24 which extend past the opposite sides of said cylinder, so that said crossheads and 5 rods form in effect a single crosshead. Each head is formed for sliding engagement with the webs and flanges of the I-beams and the latter form guides 25 for the heads.

Two pipes 26 and 27 connect the remote, 10 closed ends of the press cylinders 17 and 18 for exchanges of fluid therebetween. In the pipe 26 is a check valve 28 located adjacent the cylinder 17 and a manually operable needle valve 29 located adjacent the cylinder 18. Said check valve opens away from cylinder 17. In pipe 27 is a check valve 30 located adjacent the cylinder 18 and a manually operable needle valve 31 located adjacent cylinder 17. Check valve 30 opens away from cylinder 18. A pressure gauge 32 has a pipe connection with the closed end of cylinder 17 and a pressure gauge 33 has a pipe connection with the closed end of cylinder 18.

Connected to the crosshead 23 are pull-back means to assist in moving the connected rams and crossheads in a direction away from the crank. This means includes two arms 34 which extend laterally from opposite sides of the crosshead 23 and outwardly 30 through clearance slots 35 in the beam webs. Two pulleys 36 are mounted upon outwardly extending arms 37 supported by the beams and spaced outwardly therealong from the arms 34. Secured to the latter and trained 35 over the pulleys are cables 38 from which weights 39 are suspended. The weights tend to move the rams and crossheads to the left, with reference to the drawing.

A form of sucker rod which the apparatus 40 is designed to test is indicated at R. Such a rod is usually made in sections S each about thirty feet in length. Each section is formed with threaded ends 40, and the opposed ends of two successive sections are threaded into 45 a coupling member C. The latter is formed with threaded sockets 41 at its opposite ends to receive the ends 40 of the rod sections, and is formed with a reduced and flattened medial portion adapted to be engaged by a 50 wrench. The sections are formed with similar wrench engaging portions and are formed also with enlarged heads 42 at the roots of their threaded ends 40 to abut the ends of the coupling member.

55 A coupling member 43 is mounted upon the crank 5 for operatively and releasably connecting the rod R to the crank. This member comprises a split sectional strap 44 which defines an eye for encircling and pivotally 60 engaging the crank pin 17 and has its sections secured together by bolts. One section rigidly carries a threaded socket extension 45 into which one of the threaded ends 40 of the rod is adapted to be screwed. An- 65 other coupling member 46 is rigidly secured

to the crosshead 23 and is in the form of a threaded socket member similar to the socket extension 45 and adapted to have the opposite end of the rod R threaded into it.

The cage 4, in the present instance, is in the form of a straight, tubular metal section so proportioned and disposed between the I-beams as to surround the coupling C between the rod sections, when the rod is connected into the apparatus, and to substantially duplicate the conditions under which the coupling will have to work when confined in a well casing in actual service. 70 75

In the operation of the apparatus a length of sucker rod formed by a plurality of coupled sections is extended through the cage 4 and its opposite threaded ends 40 are screwed into the sockets 45 and 46 of the crank and the hydraulic device respectively. Between said sockets the rod is entirely unsupported so that it is free to flex and move laterally in any direction to a limited extent. An approximately correct adjustment of the needle valves 29 and 31 is made and the motor 10 is started, for rotating the crank 90 5 and reciprocating the rod. The adjustment of said valves determines the resistance which the hydraulic device will offer to the movement of the crossheads and the connected rod, and the adjustment is made in accordance with the length and strength of the rod. 95

In the drawing, a rod composed of only two sections is shown under test. The apparatus may, however, be proportioned to accommodate a longer rod. A slender rod is 100 of course much stronger under tension than under compression. Therefore the valve 31 is adjusted to materially restrict the flow from cylinder 18 to cylinder 17 and cause a 105 strong resistance in cylinder 18 to the movement of the crosshead structure to the right or toward the crank. Consequently the rod R is placed under strong tension. Valve 29, on the contrary, is opened much wider than valve 31 so that the reverse flow from cylinder 17 to cylinder 18 is much less restricted and less resistance is offered to the movement of the crossheads and the rod R toward the left. Gauge 32 indicates the hydraulic 110 resistance to the thrust of the rod and gauge 33 indicates the pull resistance imposed upon the rod. If the rod is found to be too long or too weak under thrust to push the crosshead and ram structure, with a given restriction in the valve 29, the latter is opened wider and the pull-back weights 39 operate to assist the movement. Each weight preferably has a plurality of removable sections, as indicated, so that the weights may be varied to suit different requirements. 115 120 125

Oil wells are commonly very deep and very crooked and when a long sucker rod is reciprocated in such a well it is caused to sway, flex and gyrate. Upon its downward stroke it is buckled and upon its upward stroke the 130

tension tends to straighten it. The buckling of the rod is caused mainly by the weight of the upper sections of the rod upon the lower sections, together with the resistance of the sucker, and frictional engagement of the rod sections and their couplings with the well casing. At many points along its length the rod is forced by lateral deflection into frictional contact with the well casing so that it pounds and scrapes therealong. The shock and wear of this contact and the alternate bending and straightening of the rod imposes a particularly severe strain upon the couplings, causing them to unscrew or break. The present apparatus provides for a substantial duplication of these strains in a preliminary test so that any weakness in the rod sections and their couplings can be detected before the rod is put into service. By proper adjustment of the valves and by operating the apparatus at the proper rate by the motor, through the reduction gearing, the actual pull and thrust conditions can be established as they exist in service. By changing the valve adjustments the severity of the test may be varied corresponding to the strains in wells of different depths. Observation of the gauges 32 and 33 and of the duration of the test and the number of strokes of the rod will indicate the severity of the test.

The tubular cage 4 limits the buckling of the rod and frictionally contacts it in much the same manner as a well casing. The internal diameter of the tube is properly chosen with reference to the throw of the drive crank 5 to reproduce the natural conditions. A tube or cage of any suitable length may be used. If the rod is found to buckle beyond the ends of the tube, said buckling may be limited or confined to a normal degree by merely placing heavy metal bars 47 across the beams at the necessary points and in the required number. This amounts in effect to a lengthening of the cage without objectionably obscuring the rod or obstructing its insertion and removal.

While I have shown and described a very satisfactory form of my invention and a particularly advantageous use thereof I do not wish to be limited strictly to this disclosure but reserve the right to make such changes in the structure and use of the apparatus as will lie within the scope of the claims.

55 What I claim is:

1. An apparatus for testing the couplings of sectional sucker rods, comprising a rotatably mounted crank; a crosshead; guides for said crosshead rigidly mounted in fixed relation to the crank axis at a material distance from the latter, and supporting the crosshead for reciprocation toward and from said axis; means to connect one end of a sectional coupled rod operatively and detachably to the crank; means to connect the opposite end

of said rod detachably to the crosshead; a tubular section mounted between the crank and the crosshead to surround the coupling means between the rod sections, the internal diameter of said tubular section being substantially the same as that of a well casing in which the rod is to be used; power means for rotating the crank and reciprocating the crosshead through the medium of the connected rod; and means for resisting movement of the crosshead and imposing a load upon the rod and its coupling means. 70 75

2. An apparatus for testing a long rod formed of coupled sections, comprising a rotatably mounted crank; a crosshead; guides for said crosshead rigidly mounted in fixed relation to the crank axis at a material distance from the latter, and supporting the crosshead for reciprocation toward and from said axis; means to connect one end of a sectional coupled rod operatively and detachably to the crank; means to connect the opposite end of said rod detachably to the crosshead; a cage mounted between the crank and the crosshead to surround the coupling means between the rod sections and limit buckling of the rod; power means for rotating the crank and reciprocating the crosshead through the medium of the connected rod; and means for resisting movement of the crosshead and imposing a load upon the rod and its coupling means. 80 85 90 95

3. An apparatus for testing the couplings of sectional sucker rods, comprising a rotatably mounted crank; a crosshead; guides for said crosshead rigidly mounted in fixed relation to the crank axis at a material distance from the latter, and supporting the crosshead for reciprocation toward and from said axis; means to connect one end of a sectional coupled rod operatively and detachably to the crank; means to connect the opposite end of said rod detachably to the crosshead; a tubular section mounted between the crank and the crosshead to surround the coupling means between the rod sections, the internal diameter of said tubular section being substantially the same as that of a well casing in which the rod is to be used; power means for rotating the crank and reciprocating the crosshead through the medium of the connected rod; means for resisting movement of the crosshead and imposing a load upon the rod and its coupling means; and adjustable means to vary said crosshead resistance. 100 105 110 115 120

4. An apparatus for testing the couplings of sectional sucker rods, comprising a rotatably mounted crank; a crosshead; guides for said crosshead rigidly mounted in fixed relation to the crank axis at a material distance from the latter, and supporting the crosshead for reciprocation toward and from said axis; means to connect one end of a sectional coupled rod operatively and detachably to the crank; means to connect the opposite end 125 130

of said rod detachably to the crosshead; a cage mounted between the crank and the crosshead to surround the coupling means between the rod sections and limit buckling 5 of the rod; power means for rotating the crank and reciprocating the crosshead through the medium of the connected rod; means for yieldingly resisting the reciprocation of the crosshead and thereby imposing 10 a push load and a pull load alternately upon the rod; and adjustable means for varying said push load and pull load independently of each other.

5. An apparatus for testing sectional 15 sucker rods, comprising a power-operated means adapted to be connected to one end of a sectional sucker rod to apply a push-and-pull force thereto to reciprocate said rod; a reciprocable device adapted to be connected 20 to the other end of said sucker rod; means to connect one end of a sectional coupled rod operatively and detachably to said power-operated means; means to connect the other end of said rod to the said reciprocable device; a cage between said power-operated 25 means and said reciprocable device to surround the coupling between the rod sections and permit limited lateral deflection of the coupling in any direction within the cage; means for yieldingly resisting movement of the reciprocable device in both directions and imposing a push load and a pull load alternately on the rod to alternately flex and straighten said rod; and adjustable means 30 for varying said push load and pull load independently of each other.

6. An apparatus for testing sectional 40 sucker rods, comprising a power-operated means adapted to be connected to one end of a sectional sucker rod to apply a push-and-pull force thereto to reciprocate said rod; a reciprocable device adapted to be connected to the other end of said sucker rod; means to connect one end of a sectional coupled rod 45 operatively and detachably to said power-operated means; means to connect the other end of said rod to the said reciprocable device; a cage between said power-operated means and said reciprocable device to surround the coupling between the rod sections and permit limited lateral deflection of the coupling in any direction within the cage; and means for yieldingly resisting movement 50 of the reciprocable device in both directions and thereby imposing a push load and a pull load alternately on the rod to alternately flex and straighten said rod.

7. An apparatus for testing sectional 60 sucker rods, comprising a power-operated means adapted to be connected to one end of a sectional sucker rod to apply a push-and-pull force thereto to reciprocate said rod; a reciprocable device adapted to be connected to the other end of said sucker rod; means 65 to connect one end of a sectional coupled rod

operatively and detachably to said power-operated means; means to connect the other end of said rod to the said reciprocable device; a cage between said power-operated means and said reciprocable device to surround the coupling between the rod sections and permit limited lateral deflection of the coupling within the cage; means for yieldingly resisting movement of the reciprocable device and thereby imposing a load on the rod; and 70 adjustable means for varying said load. 75

8. An apparatus for testing the couplings of sectional sucker rods, comprising a rotatably mounted crank; a crosshead; guides for said crosshead rigidly mounted in fixed relation to the crank axis at a material distance from the latter, and supporting the crosshead for reciprocation toward and from said axis; means to connect one end of a sectional coupled rod operatively and detachably to the crank; means to connect the opposite end of said rod detachably to the crosshead; a tubular section mounted between the crank and the crosshead to surround the coupling means between the rod sections, the internal 80 diameter of said tubular section being substantially the same as that of a well casing in which the rod is to be used; power means for rotating the crank and reciprocating the crosshead through the medium of the connected rod; hydraulic means for resisting movement of the crosshead and imposing a load upon the rod; and valve means for varying said resistance. 85

9. An apparatus for testing the couplings of sectional sucker rods, comprising a pair 90 of elongated beams supported in spaced parallel relation; a crank supported by said beams and mounted for rotation therebetween; a crosshead; guides for said crosshead carried by said beams and supporting the crosshead for longitudinal reciprocation between the beams toward and from the crank axis, said guides being spaced a material distance along the beams from the crank; means to connect one end of a sectional, coupled rod operatively and detachably to the crank; means to connect the opposite end of said rod detachably to the crosshead; a tubular section extending longitudinally 95 between the beams in a position between the crank and the crosshead to surround the coupling means between the rod sections, the internal diameter of said tubular section being substantially equal to that of a well casing in which the rod is to be used; means for rotating the crank and reciprocating the crosshead through the medium of the connected rod; means supported by the beams for resisting movement of the crosshead and imposing a load upon the rod; and adjustable means for varying said crosshead resistance, whereby the effects of lateral deflection 100 of the rod under a given load and of the consequent frictional contact of the coupling 105

means with the interior of said tubular section may be determined.

10. An apparatus for testing the couplings of sectional sucker rods, comprising mechanical means to detachably engage one end of a sectional coupled rod and impart a longitudinal and lateral movement to the rod similar to its normal operating movement in a well; a tubular section supported in a position to surround the coupling means between the rod sections and having an internal diameter corresponding substantially to that of a well casing in which the rod is to be used; means to impose a longitudinal stress upon the rod as it is moved; and adjustable means to vary said stress, whereby the effects of lateral deflection of the rod under a given stress and of the consequent frictional contact of the coupling means with the interior of said tubular section may be determined.

11. An apparatus for testing an elongated rod formed of coupled sections, comprising mechanical means to detachably engage one end of said rod and reciprocate it longitudinally; a tubular cage to surround the coupling means between the rod sections and limit buckling of the rod; means to impose a longitudinal stress upon the rod; and adjustable means to vary said stress, whereby the effects of lateral deflection of the rod under a given stress and of the consequent frictional contact of the coupling means with the interior of said cage may be determined.

12. An apparatus for testing a long rod formed of coupled sections, comprising power operated means adapted to be connected to one end of said rod to apply push and pull force to the rod to reciprocate it; a reciprocable device adapted to be connected to the other end of the rod; a cage between said power operated means and said reciprocable device to surround the coupling between the rod sections and permit limited flexure of the rod within the cage; and a mechanism for resisting movement of the reciprocable device in both directions comprising a pair of hydraulic cylinders, plungers in said cylinders, restricted fluid conduit means between the cylinders, and an operative connection between said reciprocable device and said plungers for shifting the latter to force fluid back and forth from one cylinder to the other as said reciprocable device is reciprocated.

13. An apparatus for testing a long rod formed of coupled sections, comprising power operated means adapted to be connected to one end of said rod to apply push and pull force to the rod to reciprocate it; a reciprocable device adapted to be connected to the other end of the rod; a cage between said power operated means and said reciprocable device to surround the coupling between the rod sections and permit limited flexure of the rod within the cage; a mechanism for resist-

ing movement of the reciprocable device in both directions comprising a pair of hydraulic cylinders, plungers in said cylinders, restricted fluid conduit means between the cylinders, and an operative connection between said reciprocable device and said plungers for shifting the latter to force fluid back and forth from one cylinder to the other as said device is reciprocated; and adjustable means to independently vary the flow of fluid in opposite directions from one cylinder to the other and thereby independently vary the push and pull resistance to the movement of the rod.

14. An apparatus for testing a long rod formed of coupled sections, comprising power operated means adapted to be connected to one end of said rod to apply push and pull force to the rod to reciprocate it; a reciprocable device adapted to be connected to the other end of the rod; a cage between said power operated means and said reciprocable device to surround the coupling between the rod sections and permit limited flexure of the rod within the cage; means for resisting movement of the reciprocable device in both directions comprising a pair of hydraulic cylinders, plungers in said cylinders, restricted fluid conduit means between the cylinders, and an operative connection between said reciprocable means and said plungers for shifting the latter to force fluid back and forth from one cylinder to the other as said device is reciprocated; and gauges to indicate the fluid pressures in the cylinders.

15. An apparatus for testing a long rod formed of coupled sections, comprising power operated means adapted to be connected to one end of said rod to apply push and pull force to the rod to reciprocate it; a reciprocable device adapted to be connected to the other end of the rod; a cage between said power operated means and said reciprocable device to surround the coupling between the rod sections and permit limited flexure of the rod within the cage; a hydraulic mechanism for resisting movement of the reciprocable device in both directions; and means to automatically assist the movement of the reciprocable device in one direction and thereby reduce thrust stress upon the rod.

16. An apparatus for testing sectional sucker rods, comprising a power-operated means adapted to be connected to one end of a sectional sucker rod to apply a push-and-pull force thereto to reciprocate said rod; a reciprocable device adapted to be connected to the other end of said sucker rod; means to connect one end of a sectional coupled rod operatively and detachably to said power-operated means; threaded coupling means to connect the other end of said rod to the said reciprocable device; a cage between said power-operated means and said reciprocable device to surround the coupling between the

rod sections and permit limited flexure of the rod within the cage; and means for yielding-
ly resisting movement of the reciprocable
device and thereby imposing a load on the
5 rod.

17. An apparatus for testing sectional sucker rods, comprising a power-operated means adapted to be connected to one end of a sectional sucker rod to apply a push-
10 and-pull force thereto to reciprocate said rod; a reciprocable device adapted to be connected to the other end of said sucker rod; means to connect one end of a sectional coupled rod operatively and detachably to said
15 power-operated means; means to detachably connect the other end of said rod to the said reciprocable device; a cage between said power-operated means and said reciprocable device to surround the coupling between the
20 rod sections and permit limited lateral deflection of the coupling within the cage; and a hydraulic mechanism for resisting movement of the reciprocable device and thereby imposing a longitudinal stress upon the rod.
25 18. An apparatus for testing a rod formed of coupled sections comprising mechanical means connectable to one end of said rod to apply longitudinal push and pull force thereto; means connectable to the opposite end
30 of the rod to resist longitudinal movement thereof by said mechanical means and cause the rod to buckle under the push force; and a cage to surround the rod coupling and limit buckling of the rod.
35 In testimony whereof I hereunto affix my
signature.
